UNITED STATES PATENT OFFICE.

MICHAEL PERRETE, OF ALLIANCE, OHIO.

FILING-CABINET.

1,225,170.

Specification of Letters Patent.

Patented May 8, 1917.

Application filed April 13, 1916. Serial No. 90,954.

To all whom it may concern:

Be it known that I, MICHAEL PERRETE, a citizen of Switzerland, residing at Alliance, in the county of Stark and State of Ohio, have invented certain new and useful Improvements in Filing-Cabinets; and I do declare the following to be a full, clear, and exact description of the invention, such as will enable others skilled in the art to which it appertains, to make and use the same.

My invention is an improved filing cabinet of the type including a rotary member having a plurality of compartments or pockets to receive therein the matter to be filed.

The main object of the invention is to provide a device of the class specified which may be simply and inexpensively manufactured and marketed, yet which regardless of these advantages, will be highly efficient and durable.

A further object of the invention is to provide means whereby the springs holders used for retaining the bills and the like within the numerous pockets, may be made to prevent accidental removal of identification cards from card holders carried by the sides of said pockets.

Yet another object is to provide an extremely simple yet efficient structure for forming the bottoms of the numerous pockets.

With these general objects in view, the invention resides in certain novel features of construction, and in unique combinations of parts to be hereinafter fully described and claimed, the descriptive matter being supplemented by the accompanying drawings which constitute a part of this application and in which:

Figure 1 is a front elevation of the improved cabinet with the door thereof swung forwardly, this door being shown in section;

Fig. 2 is a central vertical longitudinal section through the improved cabinet;

Fig. 3 is a vertical transverse section taken on the plane of the line 3—3 of Fig. 1;

Fig. 4 is a detail longitudinal section on the plane of the line 4—4 of Fig. 3; and

Fig. 5 is a perspective detail of a portion of the rotary filing member.

In specifically describing the construction shown in the drawings above briefly described, similar characters will be placed on corresponding parts through the several views, and reference will be made to the

numerous elements by their respective indices.

To this end, the numeral 1 designates broadly a substantially cylindrical casing 60 whose end walls 2 are shown as provided on their inner sides with sockets 3 to receive the journals 4 of a rotary filing member 5 which is housed within the casing. For allowing access to the member 5 at will, the 65 front of the casing 1 is provided with a hinged door 6 adapted to swing forwardly and perhaps to serve as a desk when in this position, any preferred means such as that shown at 7 being provided for holding said 70 door in closed position. In most cases, a lock will be employed for this purpose.

The rotary filing member 5 includes a pair of circular end plates 8 preferably having their edges turned laterally to form continuous reinforcing flanges 9, thereby allowing the manufacturer to construct said plates 8 of extremely thin material such as tin. Extending between the two end plates 8, is a series of radially disposed plates 10 which 75 form therebetween pockets to receive the matter to be filed, the inner edges of the numerous plates 10 being bent toward the bodies of said plates as shown at 11 and terminating in flat longitudinally disposed 80 flanges 12 which contact throughout their lengths with the adjacent faces of adjacent plates. In most cases, the flanges 12 will be soldered to the plates with which they contact, but other fastening means may well be 85 used, and in fact if the end plates 8 be disposed in rather close proximity, the flanges 12 could well be free from anchoring means.

The plates 10 may be secured in any preferred manner to the end plates 8, but the 95 ends of said plates 10 are preferably provided with tongues 13 passed through radially aligned slots 14 in said plates 8, said tongues being bent laterally as shown most clearly in Fig. 5. This is an efficient manner of anchoring the ends of the plates 10, yet it is extremely simple and inexpensive.

At suitably spaced points, the edges of the plates 10 are so cut and bent as to form card holders 15 extending laterally from 105 said edges and having inlet mouths 16 at said edges, these holders being adapted to retain identification cards by means of which the location of any desired papers may be readily ascertained. As above set forth, one of the aims of the present invention is to provide means which will prevent 110

removal of the cards from the holders 15, and will at the same time serve to prevent dislocation of the papers within the numerous pockets. To this end, curved 5 springs 17 are pivoted at 18 to the plates 10, the inner ends of said springs acting to hold the bills or other papers in the aforesaid pockets, while the outer ends of these springs are disposed opposite the mouths 16, 10 and thus said ends will prevent removal of cards from the holders 15 until the springs 17 are swung to the dotted line position indicated in Fig. 2.

By constructing the improved cabinet in 15 the manner shown and described, it may be easily manufactured at comparatively small expense, yet it will be highly efficient and durable. Obviously, the bent inner edges of the plates 10 form effective bottoms for 20 the numerous filing pockets, while the two-fold function of the springs 17 renders them highly desirable.

Preferably, though not necessarily used 25 in conjunction with the parts so far described, is a friction brake 20 forced into contact with the outer side of one of the end plates 8 by a spring 21 to normally hold the filing member 5 against rotation. A thumb lever 22 is provided, however, by means of 30 which the brake 20 may be moved from engagement with the aforesaid plate 8, thereby allowing the member 5 to be readily turned at will. The lever 22 is releasable only from the interior of the casing 1, (see Fig. 1) this 35 being particularly desirable in view of the fact that even though the cabinet be roughly handled, for instance in moving from place to place, the member 5 may not rotate accidentally. This prevents the 40 persons and the like which have been left for ready access upon opening of the door 6, from moving to other positions as will be readily understood.

From the foregoing, taken in connection 45 with the accompanying drawings, the construction, manner of operation, and numerous advantages of the improved cabinet will be readily understood without requiring a more extended explanation. In conclusion, however, 50 I will state that although a number of specific details have been shown and described for accomplishing probably the best

results, numerous changes may be made within the scope of the invention as claimed without sacrificing the main advantages 55 thereof.

I claim as my invention:

1. A device of the class described comprising, a rotary filing member including a plurality of radiating plates forming therebetween segmental pockets for papers to be filed, identification card holders carried by and extending laterally from the outer edges of said plates, said holders having inlet mouths at said edges of the plates, and paper holders carried by the aforesaid plates to hold the contents of the segmental pockets therein, said paper holders having portions normally disposed opposite said mouths to prevent removal of cards from the card 70 holders but being movably mounted to allow them to be so shifted as to readily permit the insertion or withdrawal of the aforesaid cards.

2. A device of the class described comprising, a rotary filing member including a plurality of radiating plates forming therebetween segmental pockets for papers to be filed, identification card holders carried by and extending laterally from the 80 outer edges of said plates, said holders having inlet mouths at said edges of the plates, and radially disposed springs pivoted between their ends to the sides of said plates, the outer ends of said springs being disposed 85 opposite the inlet mouths of the holders to prevent removal of the cards from the holders, while the inner ends of said springs serve to retain the numerous papers in the aforesaid pockets.

3. A device of the class described comprising a filing member including a plurality of pockets for papers to be filed, identification card holders for said pockets, and multi-function members for holding papers 95 in the pockets and for also holding the identification cards in the card holders.

In testimony whereof I have hereunto set my hand in presence of two subscribing witnesses.

MICHAEL PERRETTEN.
